UNITED STATES PATENT OFFICE.

DOUGLAS E. BONNER, OF NEW YORK, N. Y.

LIGHTING SYSTEM FOR CONVEYANCES.

Application filed June 4, 1927. Serial No. 196,421.

The invention relates to lighting systems of conveyances such as automobiles, boats, railway cars and other vehicles, and more particularly to means for illuminating the path of travel with strong, concentrated rays of lamps mounted on the conveyance.

The glare and blinding effect of strong lights on a person approaching them is generally known to be dangerous and inconvenient and presents a problem for which a satisfactory solution has been and is being sought.

An object of my invention is to provide a lighting system in which strong lights are used to brightly illuminate the path of travel for a considerable distance in advance of the conveyance without blinding persons approaching the conveyance and in a manner which permits the approaching persons to see the path between them and the conveyance.

Other objects will be apparent from the description hereinafter and the features of novelty will be pointed out in the claims.

My invention comprises strong lights, the rays of which are projected forward and intermittently extinguished, dimmed, or diverted to such an extent that they do not cause objectionable glare to persons approaching said lights.

When my lighting system is used on a conveyance, a person approaching the same, for instance, in a second conveyance provided with a light which casts a continuous or an intermittent beam ahead, is given a clear view of his path during the intervals when the intermittent lights on the first mentioned conveyance are off or dim.

With two conveyances each equipped with my system, the efficiency would be impaired if the lights of both conveyances were on in full brightness during the identical periods. To reduce the possibility of such coincidental full brightness, the lights in my system are arranged to be off or of reduced brilliancy, that is dimmed, for periods considerably longer than the periods in which said lights are on full.

The cycle of intermittent operation in my lighting system is arranged so that during the period of darkness or dimness, the conveyance will travel ahead a distance less than that disclosed during the previous period of full light. With this arrangement the entire path ahead is disclosed under strong light and furthermore is disclosed

several times, if the intermittent light cycle is comparatively short.

A preferred arrangement of my system may be illustrated as follows in connection with a conveyance assumed to be traveling at thirty miles per hour and equipped with lights which when on full disclose the path for approximately one hundred feet ahead. If the cycle of intermittent illumination is arranged to be one second with a period of $\frac{1}{3}$ second on full and $\frac{2}{3}$ of a second off or dim, the conveyance covers a distance of $29\frac{1}{3}$ feet during periods when the lights are off or dim, which is only approximately $\frac{29}{100}$ of the extent of the path seen during the previous period of full illumination. Hence any spot in the path will be disclosed approximately three times, that is to say, on the occasion of three different periods of full illumination which provides ample disclosure for safe travel.

I have found that lights can be arranged to fully disclose the path ahead for over thirty feet with rays reduced, dimmed or diverted to an extent which does not blind approaching persons to any appreciable extent. Therefore by arranging the lights in my system so that instead of becoming extinguished during the periods of darkness they are reduced or dimmed as described above, I provide continuous and uninterrupted full disclosures of the path ahead of the traveling conveyance. This feature eliminates a feeling of unsafeness which might come to timid or inexperienced persons in the conveyance during periods of complete darkness, even if these periods were short.

While I prefer to use the same lamps for the strong long distance light and for the dim shorter light, it is to be understood that similar results may be obtained by using two sets of lamps or by using an electric lamp containing two filaments, one for strong and another for less powerful illumination.

Referring to the drawings which are in diagrammatic form, Fig. 1 shows my lighting system operated by a motor driven circuit breaker; and Fig. 2 shows a thermostatic device of well known form employed to make and break the circuit.

Referring to Fig. 1, 13 is an electric battery, one side of which is connected to one side of lamps 10, and 20 is a motor having a circuit breaking commutator with a section 16 of its periphery grounded to the motor shaft 18 and a section 17 insulated

- therefrom. A bracket 19 is grounded to the commutator and connected to the other side of the lamps 10, while 15 is a brush in contact with the commutator and connected 5 with a side of the battery through an on and off switch S. Leads A and B extend from the field and armature of the motor to the battery through which the current for running the motor 20 is transmitted.
- 10 A variable resistance R^2 is provided for regulating the speed of the motor, and a variable resistance R' shunted around the circuit breaking commutator. When the motor revolves, the circuit to the lamps is 15 made and broken by the commutator, so that when said circuit is broken a diminished current passes through resistance R' to the lamps which causes them to remain lighted to any desired degree of intensity 20 less than the maximum intensity of said lamps when the circuit is broken.
- Fig. 2 shows an arrangement similar to that of Fig. 1 but with a thermostatic circuit breaker substituted for the motor. In 25 this arrangement 23 is a strip of insulating material, 26 thermostatic metal, and 27 a coil with one end grounded to the thermostatic metal and the other end connected to one side of the battery and lamps. The 30 other side of the lamps are connected with a screw 25 in electrical connection with the thermostatic metal 26. A contact screw 24 is connected with the battery 13 and is intermittently in contact with the thermostatic 35 metal 26, an on and off switch S being located in the connection from the contact screw 24 to the battery 13. When this switch S is closed, full current passes to the lamps in full brilliance. At the same time 40 current passes through the coil 27 and by heating the thermostatic metal 26 causes the same to flex downwardly away from the contact screw 24 thereby breaking the direct circuit to the lamps 10. At this time 45 the lamps receive diminished current to any desired extent through the variable resistance R' and accordingly become dim instead of going out altogether. The thermostatic circuit breaker is made so that the period 50 during which the main circuit to the lamps is broken is longer than the period during which said circuit is closed.
- It will be understood that the principles 55 of the invention are not limited to the specific types of circuit breakers shown in Figs. 1 and 2 of the drawings, but that any suitable or well known equivalent devices can be employed for accomplishing the same purpose.
- 60 Various changes in the forms diagrammatically shown and described may be made within the scope of the claims without departing from the spirit of the invention.
- I claim:
- 65 1. In combination with a conveyance,
- illuminating means mounted on said conveyance and adapted to project rays of light in the direction of travel, and means operating to intermittently vary the intensity of the light within a maximum and minimum range, the periods of minimum intensity being longer than the periods of maximum intensity and occurring in such sequence as to provide illumination. 70
2. In combination with a conveyance, electric illuminating means mounted on said conveyance and adapted to project rays of light in the direction of travel of the vehicle, a source of electric energy in circuit with the illuminating means, and means associated 75 with the circuit operating to intermittently change the amount of current flowing through the circuit and thereby vary the intensity of the rays emitted by the illuminating means, the said current changing means being arranged to make the periods of lower intensity longer in duration than the periods of higher intensity, whereby glare of the lights is reduced. 80
3. In combination with a conveyance, electric illuminating means mounted thereon and adapted to project rays of light in advance of the conveyance and in the path thereof, a source of electric energy in circuit with the illuminating means, an automatic circuit breaker in said circuit for making and breaking said circuit intermittently whereby the intensity of the light is varied over a predetermined range, and a variable resistance shunted across said circuit breaker so that 90 the lights will become dim to any predetermined degree instead of going out. 100
4. The method of illuminating the path of travel of conveyances which consists in projecting in advance of the conveyance rays of light of such intensity as to produce a glare in the eyes of an observer when viewed from a point near the center of illumination, and regularly and periodically interrupting the projection of said rays at such time intervals as to reduce the glare thereof, the periods of interruption being longer than the periods of projection. 110
5. Illuminating means for a conveyance comprising means on said conveyance for projecting in the path of travel thereof rays of light of such intensity as to produce a glare when observed from a point near the center of illumination, and means for regularly and periodically interrupting the projection of said rays to reduce the glare thereof, the said interrupting means being constructed and arranged to cause the periods of projection to be less than the periods of interruption. 115
6. Illuminating means for a conveyance comprising means for projecting rays of light of relatively high intensity in the direction of travel, and means for regularly and periodically substituting for the light of 120
- 125

high intensity rays of light of materially less intensity whereby glare of the lights will be reduced.

7. Illuminating means for a conveyance comprising means for projecting rays of light of relatively long range in the direction of travel, means for regularly and periodically substituting for the light of long range rays of light of materially shorter range, the periods of light of shorter range being materially longer than the periods of light of greater range, whereby the predominating effect will be that produced by the light of shorter range.

15 8. Illuminating means for a conveyance

comprising means for projecting rays of light in the direction of travel, means for supplying energy to said projecting means to produce light rays of relatively long range, means for regularly and periodically interrupting the supply of energy and for supplying energy to said projecting means to produce light rays of materially shorter range during the periods of interruption of said first named supply of energy, said light rays of less range being sufficient to illuminate the path of travel.

In testimony whereof I have hereunto set my hand.

DOUGLAS E. BONNER.
